[57] **CLAIM**

The ornamental design for a binding strip, as shown and described.

DESCRIPTION

FIG. 1 is a perspective view of a binding strip showing our new design;

FIG. 2 is an end elevational view thereof;

FIG. 3 is a top plan view thereof;

FIG. 4 is a side elevational view thereof;

FIG. 5 is a bottom plan view thereof; and

FIG. 6 is an enlarged perspective view of a portion thereof.
